DROP HAMMER

Application filed May 17, 1929. Serial No. 363,921.

The present invention relates to improvements in drop hammers, and has for an object to provide an improved roll driving arrangement for drop hammers, in which vibration is largely eliminated with economies in construction and operation, and with increases in strength, stability and durability.

Heretofore factories employing drop hammers have been expensively equipped with over-head pulleys and shafting for carrying the source of power to the various drop hammers. Some effort has been made to eliminate this expensive equipment and to clear the factories of all such overhead pulleys and shafting by the substitution of electric drives for the individual machines, but such prior attempts have not signally succeeded, owing to the fact that the introduction of the electric drive has given rise to other difficulties and problems largely involving maintenance costs, vibration, excessive wear and tear on the machines, etc.

It is an object of the invention to provide an improved construction for direct motor driven drop hammers, in which the rolls for raising the hammer are driven by two electric driving mechanisms, the arrangement being such that a certain balance and equilibrium are obtained both statically and dynamically, accompanied by a decided decrease in, if not an entire elimination of, vibration and its resulting objectionable wear and tear.

A further aim is to provide an improved arrangement which is characterized by its simplicity and ruggedness in construction, and by its ability to stand up under the strains and shocks to which it must be subjected, thus materially reducing operating and maintenance costs.

A further object of the invention resides in providing an improved head construction for drop hammers in which a compact assembly is provided, the various units being distributed and arranged symmetrically and so coordinated and related that the same are exposed for access in repair and replacement.

A still further object of the invention resides in providing an improved drop ham-

mer construction in which the hammer raising rolls are independently and synchronously driven in a smooth and effective manner by separate drive means.

Other objects will be in part obvious and in part pointed out more in detail herein-after.

The invention accordingly consists in the features of construction, combination of elements and arrangement of parts which will be exemplified in the construction herein-after set forth and the scope of the application of which will be indicated in the appended claims.

In the drawings, wherein like symbols refer to like or corresponding parts throughout the several views,

Figure 1 is a front elevation of an improved drop hammer constructed in accordance with the present invention.

Fig. 2 is an enlarged top plan view of the same.

Fig. 3 is a horizontal section taken on the line 3—3 in Figure 4.

Fig. 4 is a vertical section taken on the line 4—4 in Figure 5, and

Fig. 5 is a vertical section taken on the line 5—5 in Figure 4.

Referring more particularly to the drawings, 10 designates the base, and 11, the uprights having the guideways 12 for the hammer 13. The hammer board is represented at 14 and it passes up through the head of the machine. The friction bar is adapted, in the customary manner, to operate the eccentrics for the front roll 42 for moving that roll into and out of engagement with the board 14. An adjustable bar 16 may be connected to the eccentrics for the rear roll 41 for the purpose of adjusting the rear roll relative to the hammer board and the front roll. The front clamp (not shown) may be operated by the rod 17 from the treadle 18 carried by the base 10. The rear clamp (not shown) may be adjusted, in the usual manner, through the rod 17'. The base 10 supports the lower die 19.

The parts and elements of the hammer above described are old and well-known and, therefore, they are not completely illustrated

nor described in detail. It is understood, of course, that the present disclosure is by way of illustration only, it being obvious that the improvements of the present invention may 5 be incorporated in drop hammers generally, and that the hammer is susceptible to various modifications and changes. In the present instance there is shown a single pair of hammer lifting rolls, but it is obvious that 10 a plurality of steps of rolls arranged one above the other may be provided. It is also apparent that the eccentrics in which the hammer roll shafts are journaled may be variously adjusted and controlled, and this 15 is also true of the board clamps.

The present invention relates more particularly to the head of the machine and driving means for the rolls. The head, which comprises the sections 15 and 20, is so constructed that it may replace the heads of the present machine without changing the construction of the standards or uprights 11. To this end, the bottom portion of the lower head section 15 is formed similarly to the 25 lower ends of heads as heretofore constructed. The upper head section 20 supports the roll driving mechanisms, that will now be described. As shown in Figure 2, an electric motor 21 is installed upon the head section 30 or platform 20 at one corner thereof. The armature shaft 22 of this motor extends out from the motor and to a flexible or other connection of connector 23, through which the motor is coupled to a shaft 24 of a gear 35 reduction unit 25.

This reduction unit may be of any appropriate internal construction (not shown), the same forming no part of the present invention. The unit 25 is installed at a corner of 40 the head section 20 in axial line with the motor 21, the motor 21, coupling 23 and connected reduction unit 25 being all disposed to one side in the present instance, the rear side of the center of the head section 20. In like 45 manner an electric motor 26, flexible or other coupling 27 and connected gear reduction unit 28 are mounted at the other side, (i. e. front side) of the center of the section 20, except that in this case the parts are reversed as to position; namely, the electric 50 motor 26 is disposed on the left side of the head, while the gear reduction unit 28 is disposed on the right side of the head. In the center of the section 20 is a slot 29 to receive 55 the board 14 carrying the drop hammer 13.

Referring more particularly to Figure 4, a shaft 30 is shown as extending out from the gear reduction unit 25 and being the follower or driven shaft of such unit. This shaft projects beyond the upper head section 20 at the left hand side and receives the sprocket wheel 31 which is made fast thereon. The sprocket wheel is engaged by a chain 32 which extends down to a second sprocket wheel 33 65 on the roll shaft 34. The sprockets and chain

are preferably contained within a housing 35.

In a similar way, the gear reduction unit 28 at the opposite side of the head frame carries a sprocket 36 coupled by a chain 37 to the sprocket 38 on the companion roll 70 shaft 39. The last mentioned sprocket and chain gearing are contained in a housing 40 at the end of the machine opposite the housing 35.

Viewing Figure 3, the roll shafts 34 and 39 75 are shown as having fixedly mounted thereon the usual rolls 41 and 42, respectively, and between which the board 14 extends. The shaft 34 is journaled in the usual eccentrics 43 mounted in the half bearings 44 of the 80 lower head section 15. The eccentrics 43 are connected by a yoke 43' to which the adjustable bar 16' may be connected in the usual manner. The roll shaft 39 is journaled in the eccentrics 45 mounted in the half bearings 85 46 of the lower head section 15. The eccentrics 45 are connected by a yoke 45' and are adapted to be turned within the bearings 46 by the friction bar 16 in a well known manner.

Viewing Figure 5, the upper head section extends down to the shafts 34 and 39 and is provided with half bearings 47, being complements of the bearings 44 and 46 of the lower head section 15, and adapted to cooperate with such half bearings for confining the eccentrics and the roll shafts in the head frame. The upper head section is formed with the end walls 48 and 49 and with the strengthening webs 50 and 51. Intermediately, as shown in Figure 5, the lower portion of the upper head section is cut away as indicated at 52 and the walls 53 of the slot 29 extend down to this cut away portion 52. A light cellular, yet strong construction is 100 imparted to the upper head section by the arrangement just described.

The motors are supported upon pairs of brackets 54 and 55 preferably cast with the upper head section and extending above the 110 platform 20. These brackets 54 and 55 have mutually out-turned flanges 56 and 57 on which the supports for the motors directly rest and are secured as by means of the bolts or other fastenings 58. Reinforcing webs 59 and 60 are cast or otherwise produced between the respective flanges, brackets and the platform 20. In like manner, the gear reduction units are carried upon spaced supports 61 having flanges 62 reinforced by the 115 webs 63 and 64. The units are bolted or otherwise secured to the reinforced and flanged brackets.

In the use of the hammer, the motors individually and respectively drive the flexible couplings 23 and 27 and their reduction gear units 25 and 28 whereby the armature shaft speeds of the motors will be stepped down to a requisite speed for driving the rolls 41 and 42 through the individual chain 130

drive connections. Thus each roll is driven independently of the other one, there being no mechanical driving connection therebetween. The motors 21 and 26 are synchronized in all respects, however, so that the two hammer rolls are driven at the same speed and under like torque. The motors may be connected to a single switch 65. The rolls 41 and 42 grip the board 14 and raise the hammer 13 just as heretofore, the clamps (not shown) are adapted to grip the board and release the same on operation of the treadle 18; and the roller 42, through the action of the friction bar 16 and the eccentrics 45, is moved into and out of gripping engagement with the board 14, all in a manner which is well known in this art. As stated, the reduction units may be of standard construction and, therefore, they are not shown in detail. They may be of the type having a drive shaft (such as the shaft 24), a driven or follower shaft (such as the shaft 30) and an intermediate shaft which is designated by the numeral 66. A small gear on the drive shaft meshes with a larger gear on the intermediate shaft, and a small gear on the latter shaft meshes with a large gear on the driver shaft.

The flexible or other couplings 23 and 27 may be enlarged as to one or both of their elements or large collars may be included in the coupling constructions to act as fly wheels for the motors or the sprockets on the gear reduction shafts might be enlarged and weighted to act as fly wheels.

It will be noted, particularly from Figure 2, that a condition of symmetry prevails in the distribution of the units upon the platform 20. One power train is located at one side of the longitudinal center of the platform; while the opposite power train is disposed to the other side of such center. If we view the transverse center of the platform as being at right angles to the longitudinal center and postulating that the transverse center passes through the couplings 23 and 27, it will be apparent that a like condition of symmetry prevails as regards this transverse center line. In other words an electric motor and a gear reduction unit is disposed to each side of the transverse center, the places of the motor and reduction unit being reversed upon opposite sides of the transverse center, just as they are upon opposite sides of the longitudinal center line of the platform.

This disposition of the parts creates weight balance which is important in eliminating vibration. Moreover, the synchronous operation of the motors will assist in this respect and the fact that two motors are provided to individually drive the roll shafts will also eliminate vibration particularly if the motors are synchronized. Especially is this latter fact so where the motors are disposed at relatively opposite positions upon

the head frame. In such relative positions the speedily rotating armature shafts turn in relatively opposite directions and they dynamically balance one another and create a condition of stability in the head, enhance equilibrium and to this extent decrease the vibration. Not only are the motors themselves dynamically balanced, but the turning moments of the motor armatures, as well as corresponding shafts and gears of the reduction units, are dynamically balanced. The vibration is objectionable because of the wear and tear and these are largely if not wholly eliminated by the symmetrical arrangement and the balanced condition of the units.

It will be observed that the driving units are disposed upon the top of the head frame within the limits of the base 10. These driving units add weight to the top of the machine, and this added weight tends to reduce the vibration of the top of the machine. If it were attempted to support these driving units so that they overhung, the tendency would be to accelerate or accentuate the vibration of the machine, and such strains and stresses would be set up as would tend to jar the connections loose. It will also be observed that the sprocket chains form what may be termed flexible yet positive connections between the slow speed sides of the reduction gearings and the roll shafts. Such a connection is a distinct advantage in my arrangement, as it relieves, to a large extent, the shocks and jars which would otherwise be transmitted to the reduction unit and motor when the rolls pick up the board without, however, introducing any slippage, such as would be produced if belts were employed. It is understood that the motors and reduction units are continuously driven, and when the hammer drops down the rolls are free of the hammer board so that there is but little strain upon the driving instrumentalities. When the rolls are moved against the board to effect a lifting movement of the weight, considerable strains and stresses are very suddenly brought into play, as the inertia of the hammer must be overcome, and after the hammer starts to rise these stresses and strains are somewhat smoothed out. When the rolls initially pick up the board, the transmittal of the strains and stresses to the reduction units are somewhat cushioned by the sprocket chains, which tend to flex or elongate slightly. Of course, this cushioning action takes place in a very small fraction of time, indeed, almost instantaneously, but nevertheless it is sufficiently pronounced, from the practical standpoint, to materially reduce the shocks which would be transmitted to the reduction units and the motors were the connection between these units and the rolls rigid.

The device will operate more smoothly and there is no slippage or lost motion as between

the intermeshing gear wheels heretofore employed in this art for transferring the power from the motor at one side to the roll shaft at the other side.

- 5 It is obvious that various changes and modifications may be made in the details of construction and design of the above specifically described embodiment of this invention without departing from the spirit thereof, such 10 changes and modifications being restricted only by the scope of the following claims.

I claim as my invention:

1. In a drop hammer, a board connected 15 to the hammer, a head frame, opposed rolls in the head frame for gripping opposite sides of the board, an electric motor installed on each side of the hammer board and turned relatively so that the armature shafts thereof rotate in opposite directions, gear reduction 20 units installed on the opposite sides of the hammer board and coupled to said motors at such sides, said motors and reduction units being positioned diagonally with respect to the center of the head frame to 25 effect weight balance and each motor and its reduction unit being equally balanced in weight with respect to the other motor and its reduction unit, and individual sprocket chains between said units and the independent rolls.
2. In a drop hammer, a board connected 30 to the hammer, a head frame, opposed rolls in the head frame for gripping opposite sides of the board, a pair of electric motors mounted on the head frame in diagonal spaced relation and with the respective armature shafts parallel, gear reduction units coupled to the armature shafts also placed diagonally with respect to one another, and 35 individual sprocket chains between the units and rolls.

3. In a drop hammer, a board connected 40 to the hammer, a head frame, lifting rolls in the head frame for gripping opposite sides of the board, a pair of synchronized individual electric motors positioned in diagonal relation to one another on the head frame and within the same, armature shafts mounted in each of the electric motors to rotate individually, gear reduction units coupled to the respective armature shafts also mounted in diagonal relation and within the head frame whereby the weight of the electric motors and gear reduction units will exert a 50 uniform pressure on the lower parts of the drop hammer, and individual sprocket chains between the units and rolls.

4. In a drop hammer, a board connected 60 to the hammer, a head frame providing a flat rectangular platform with a central opening for the passage of the hammer board opposed rolls in the head frame for gripping the opposite sides of the board, a pair of synchronized individual electric motors diagonally mounted on the platform provided 65

with individual armature shafts to rotate in parallel relation on opposite sides of the central opening, gear reduction units coupled to each of the individual armature shafts also diagonally placed with respect to one another, and individual sprocket chains between the units and rolls.

5. In a drop hammer, a board connected to the hammer, a head frame, opposed rolls in the head frame for gripping opposite sides of the board, a pair of electric motors mounted on the head frame in diagonal spaced relation, separate gear reduction units on the frame coupled to the respective motors and placed diagonally with respect to one another, and drive connections between said units and rolls, the diagonal of the gear units being substantially at right angles to the diagonal of the motors.

6. In a drop hammer, a board connected 85 to the hammer, a head frame, opposed rolls in the head frame for gripping opposite sides of the board, an electric motor installed on each side of the hammer board and turned relatively so that the armature shafts thereof rotate in opposite directions, and gear reducing mechanism interposed between each motor and a respective roll, said gear reduction mechanisms being installed on opposite sides of the hammer board, said 90 motors being positioned diagonally in one direction with respect to the head frame, the reduction mechanisms being diagonally positioned in the other direction with respect to the head frame, whereby to effect a weight balance, each motor and its reduction mechanism being equally balanced in weight with respect to the other motor and its reduction mechanism.
